UNITED STATES PATENT OFFICE

103,394

DESIGN FOR AN ILLUMINATED ADVERTISING DEVICE

John Frei, Jr., Chicago, Ill.

Application March 20, 1936, Serial No. 61,715

Term of patent 14 years

To all whom it may concern:

Be it known that I, John Frei, Jr., a citizen of the United States, residing at Chicago, in the county of Cook and State of Illinois, have invented a new, original, and ornamental Design for Illuminated Advertising Device, of which the following is a specification, reference being had to the accompanying drawing, forming a part thereof.

The single figure of the drawing is a perspective view of an illuminated advertising device showing my new design.

The plurality of light transmitting elements in the form of glass rods each having an ornamental device adjacent its lower end and an element to be illuminated at its upper end, together with the surface ornamentation of the risers of the tiers, as shown, constitute the dominant features of my design.

I claim:

The ornamental design for an illuminated advertising device, as shown and described.

JOHN FREI, JR.
